UNITED STATES PATENT OFFICE.

ANDREW COCHRAN, OF TRENTON, NEW JERSEY.

DESIGN FOR A LAVATORY OR WASHSTAND.

45,289.

Specification for Design.

Patented Feb. 24, 1914.

Application filed December 11, 1913. Serial No. 806,120. Term of patent 3½ years.

To all whom it may concern:

Be it known that I, ANDREW COCHRAN, a citizen of the United States, and a resident of Trenton, Mercer county, New Jersey, have invented a new, original, and ornamental Design for a Lavatory or Washstand, of which the following is a specification, reference being had to the accompanying drawing, in which—

Figure 1, is a front elevation of the lavatory or washstand, and Fig. 2, is a perspective view looking toward the right-hand side of the same.

I claim:

The ornamental design for a lavatory or washstand, substantially as described and as shown in the accompanying drawing.

In testimony whereof, I have signed my name to this specification, in the presence of two subscribing witnesses.

ANDREW COCHRAN.

Witnesses:

CATHARINE PIPPEL,
ELLIS L. PIERSON.
